COMBINED COVER AND INDEX FOR TELEPHONES

Arnold Neustadter, New York, N. Y.

Application May 13, 1953, Serial No. 24,994

Term of patent 14 years

(Cl. D26—14)

To all whom it may concern:

Be it known that I, Arnold Neustadter, a citizen of the United States of America, residing in New York city, State of New York, have invented a new, original, and ornamental Design for a Combined Cover and Index for Telephones, of which the following is a specification, reference being had to the accompanying drawing, forming a part hereof.

Figure 1 is a perspective view of a combined cover and index for telephones, showing my new design, and

Figure 2 is a somewhat similar perspective view of said combined cover and index, in which, how-

ever, said index is illustrated in a forwardly extended or open position.

I claim:

The ornamental design for a combined cover and index for telephones, as shown.
